Inventor:

August Sturm
by my App'tee

UNITED STATES PATENT OFFICE

AUGUST STURM, OF NEW YORK, N. Y., ASSIGNOR TO ROBERTS MANUFACTURING COMPANY, OF SAME PLACE.

DESIGN FOR TRIMMING.

Specification forming part of Design No. **9,855**, dated March 13, 1877; application filed January 27, 1877.
[Term of Patent 3½ years.]

To all whom it may concern:

Be it known that I, AUGUST STURM, of the city, county, and State of New York, have invented a certain new and useful and original Design for Trimming, of which the following is a specification:

In order to produce the trimming in accordance with the design which I have invented, I take a straight strip of goods, such as crape, tarletan, or other light material. This strip I plait, and then give the strip an undulating form from end to end, it being held in this form by being attached by size to a straight string or thread. This completes the trimming, (shown in Fig. 1,) which can be used in many connections, either alone or incorpo-

rated into other articles. It may be used, for instance, as a heading for ruffling, as indicated in Fig. 2 at *a*; or it may be used in "collarets," as shown at *b*, Fig. 3.

What I claim as my invention, and desire to secure by Letters Patent, is—

The design for trimming herein described, and shown in Fig. 1 of the accompanying drawing, consisting of a strip of goods plaited and undulated, as set forth.

In testimony whereof I have hereunto signed my name this 25th day of January, 1877.

A. STURM.
